UNITED STATES PATENT OFFICE.

HAROLD A. WILCOX, OF WEBSTER, MASSACHUSETTS, ASSIGNOR TO RODNEY HUNT MACHINE COMPANY, OF ORANGE, MASSACHUSETTS, A CORPORATION OF MASSACHUSETTS.

REEL.

Application filed April 30, 1923. Serial No. 635,423.

To all whom it may concern:

Be it known that I, HAROLD A. WILCOX, a citizen of the United States, residing at Webster, in the county of Worcester and 5 State of Massachusetts, have invented a new and useful Reel, of which the following is a specification.

This invention relates to a reel capable of general application but particularly 10 designed for use in handling cloth in a dye kettle.

It is a general object of my invention to provide a reel for such purposes, so 15 designed that it can be readily assembled and repaired and that it will be reliable and effective in use.

With this general object in view, an important feature of my invention relates to the provision of a reel having separable 20 heads or spiders of special design, whereby removal or replacement of any head or or the supporting shaft may be conveniently accomplished.

Another object is to provide improved 25 means for securing the slats or bars to the reel and for holding them in position against the pull of the cloth.

Other features of my invention relate to the provision of sectional end flanges for 30 the reel and to improved securing means therefor; to the provision of a protective casing for the shaft between the heads or spiders of the reel, and to other arrangements and combinations of parts which 35 will be hereinafter described and more particularly pointed out in the appended claims.

A preferred form of the invention is shown in the drawings, in which—

40 Fig. 1 is a front elevation of my improved reel, broken away to reduce its length;

Fig. 2 is an end view thereof;

45 Fig. 3 is a detail sectional view of one of the slats or bars, taken along the line 3—3 in Fig. 1;

Fig. 4 is a sectional end elevation taken along the line 4—4 in Fig. 1;

50 Fig. 5 is a detail longitudinal sectional view, taken along the line 5—5 in Fig. 4 and showing one half of a head or spider; and

55 Figs. 6, 7 and 8 are detail sectional views, taken along the lines 6—6, 7—7 and 8—8 in Fig. 4 respectively.

Referring to the drawings, I have shown a reel particularly adapted for use in dye kettles or for other similar purposes and comprising a supporting shaft 10, a plurality of heads or spiders 11, and a series 60 of axially extending slats or bars 12 supported by the spiders 11.

Each head or spider 11 is formed of two parts 11^a and 11^b secured together by bolts 13 (Figs. 2 and 4) which connect associated 65 flanges 14 extending inwardly from adjacent rim portions of the head. Additional bolts 15 extend through and firmly unite the hub sections of the two parts of the head.

It will be evident that a head or spider 70 thus constructed may be loosened and entirely removed from the shaft 10 by simply taking out the bolts 13 and 15. In the previous practice it has been necessary to drive the shaft axially through the hub of 75 the head in order to remove the latter, an operation which was practically impossible to perform after the reel had been used a short length of time, as the parts became 80 rusted together by the action of the acid in the dye liquor.

The heads or spiders 11 have special provision for securing the bars or slats 12 thereto and in the preferred form I provide a series of short lugs 16 each engaging 85 the front face of one of the slats 12 and a corresponding number of longer projections or arms 17 engaging the rear faces of the bars 12. Bolts 18 extend through the bars 12 and the projections 17, and also 90 preferably through a plate 19 above the lugs 16 but separate therefrom. I find that the bolts 18 hold the slats or bars much more securely when they are provided with a separate plate 19 instead of passing 95 through two fixed projections, as the plate 19 can be drawn firmly against the face of the slat or bar, whereas the distance between fixed projections cannot be varied if the bars are too thin or if they change in 100 thickness during use.

Web or flanges 20 are preferably provided for the projections 17, to take the pressure of the bars 12 due to the pull of the cloth thereon. The spoke and rim section of the heads are also reinforced by flanges as indicated in Figs. 7 and 8 and the whole structure is of a strong and rigid design well adapted to the heavy strain to which it is subjected. Each head is prefer- 105 110

ably held from rotation relatively to the shaft 10 by a key 21 and set screw 22 (Fig. 4).

The outer ends of the hub openings are 5 preferably recessed sufficiently to receive the ends of thin tubes 23 which entirely surround the shaft 10 between the heads 11 and protect the intermediate portion of the shaft from corrosion. These tubes 23 are 10 preferably made of copper or some other substantially non-corrosive material.

It is desirable that provision be made at the ends of the reel to prevent the cloth from running off of the bars 12 and for this 15 purpose I provide flange sections 25 (Fig. 2), preferably of oak or other hard wood and secured to the ends of the reel by plates 26 and bolts 27. The bolts 27 extend between the ends of adjacent flanges 25 and 20 through longitudinal holes in the bars 12 into transverse recesses 28 in which nuts 29 are retained by plugs 30 (Fig. 3). The bolts 27 when threaded into the nuts 29 are effective to draw the flanges 25 firmly 25 against the ends of the bars 12 and heads 11 and prevent displacement therefrom.

The reel herein described has been found in practical commercial use to possess important advantages over the structures previously known and commonly used, particularly by permitting easy and convenient repair and removal of a bar 12 or head 11 without disassembling the entire reel to remove the defective part. It is also found 30 that all parts of my improved reel are of adequate strength and that the parts retain their desired relation during long periods of use.

Having thus described my invention and 40 the advantages thereof, I do not wish to be limited to the details herein disclosed otherwise than as set forth in the claims but what I claim is:—

1. A reel having, in combination, a supporting shaft, a plurality of heads spaced along said shaft, a plurality of bars mounted on said heads and secured thereto, said heads having hubs with axial openings therein recessed at the outer ends, and non-corrosive 45 tubes enclosing said shaft between said

heads and having their ends secured in the recessed portions of said openings.

2. A reel having, in combination, a supporting shaft, a plurality of heads spaced along said shaft, and a plurality of bars mounted on said heads and secured thereto, said heads having relatively short lugs positioned in front of said bars, longer projections behind said bars, and bolts securing said bars to said longer projections only. 60

3. A reel having, in combination, a supporting shaft, a plurality of heads spaced along said shaft, and a plurality of bars mounted on said heads and secured thereto, said heads having relatively short lugs positioned in front of said bars, longer projections behind said bars, plates for said bars, and bolts extending through said bars, plates and longer projections and securing said bars in position. 65

4. A reel having, in combination, a supporting shaft, a plurality of heads spaced along said shaft, and a plurality of bars mounted on said heads and secured thereto, said heads having relatively short lugs positioned in front of said bars, longer projections behind said bars, bolts securing said bars to said longer projections only, and reinforcing webs at the rear of said longer projections. 75

5. A reel having, in combination, a supporting shaft, a plurality of heads spaced along said shaft, a plurality of bars mounted on said heads and secured thereto, sectional end flanges for said reel, and means to secure said flanges in position. 80

6. A reel having, in combination, a supporting shaft, a plurality of heads spaced along said shaft, a plurality of bars mounted on said heads and secured thereto, sectional end flanges for said reel, and means to secure said flanges in position, said means comprising clamping bolts extending into longitudinal openings in said bars and engaging nuts positioned in transverse openings in said bars. 90

In testimony whereof I have hereunto affixed my signature.

HAROLD A. WILCOX.
